APPARATUS FOR SEPARATING THE CONSTITUENTS OF PETROLEUM EMULSIONS

Gale L. Adams, Los Angeles, and Roy G. Barlow, Whittier, Calif., assignors to Socony-Vacuum Oil Company, Incorporated, New York, N. Y., a corporation of New York

Original application August 23, 1938, Serial No. 226,292. Divided and this application October 17, 1939, Serial No. 299,842

2 Claims. (Cl. 252—360)

This application is a division of our co-pending application Serial No. 226,292, filed August 23, 1938, and entitled Method of separating the constituents of petroleum emulsions.

The object of the invention is to continuously separate the phases of a flowing stream of petroleum emulsion after said emulsion has been resolved by the application of an electrical stress or flow.

The art of electrical dehydration is extremely voluminous and great numbers of devices for the application of an electrostatic or electrical effect to emulsions have been proposed. In almost all of these devices the electrodes are submerged in a relatively large body of emulsion which changes in characteristics as the demulsification proceeds, and while many of these devices are continuously fed and discharged, they store a considerable quantity of emulsion and its resolution products and gravity is depended on for the parting of the resolved phases.

Certain devices known as flow-stream treaters have been proposed, in which there is no storage space and the electrostatic or electrical effect is applied to a flowing stream of emulsion, these devices delivering a stream in which the emulsion is resolved but the phases are not yet separated, that is to say, a stream of oil containing in suspension the water of the emulsion, in drops and droplets of various sizes.

These flow-stream treaters labor under the disadvantage that, no matter how complete the resolution of the emulsion by the electrical effect, the discharged stream contains, not only the oil and water originally present in the emulsion, but also the emulsifying agent; usually a relatively small proportion of some very finely divided solid such as clay, shale, or asphaltic wax. In the presence of this emulsifying agent the resolved phases are highly prone to reemulsify as soon as the stream passes out of the zone in which it is subjected to electrical stress, particularly if the stream is brought to a condition of turbulence at any point prior to that at which the emulsifying agent has been removed. In practice it has been found difficult to introduce the resolved stream into a settling tank without causing a very undesirable amount of reemulsification of the constituents of the stream.

The aim of the present invention is to take the stream of resolution products from a flow-stream electrical treater and to separate or part the oil, water, and emulsifying agent without turbulence and without the danger of reemulsifying the once-resolved products. In accomplishing

this aim I make use of centrifugal force for effecting a rapid separation of the phases in a manner exemplified in the attached drawings, in which

5 Fig. 1 represents the entire apparatus in elevation and partial vertical section;

Fig. 2 is a plan view of the centrifugal unit and

Fig. 3 is a section on an enlarged scale of the collectors indicated at 34 and 39 of Figs. 1 and 2.

Fig. 4 is a vertical sectional view through a modified form of centrifugal unit.

Referring to the drawings, the flow stream treater indicated at 10 is that described in U. S. Patent 2,092,491 to Adams and Barlow, and reference is made to this patent for details as to the construction and operation of the device. Other forms of flow-stream or pipe-line treaters may be substituted if desired, as for example that shown in Fig. 2 of U. S. Patent 2,083,800 to William Woelflin, but any treating means so substituted must be deprived of any settling tank or other reservoir for treated oil and must be connected to discharge directly into the zone in which the centrifugal force is applied.

The supply of emulsion to be treated enters treater 10 through pipe 11 and control valve 12, under gravity or pump impulsion and from a source of supply not shown. In the treater the stream is subjected to an electrical stress or flow, as may be, and is thereby resolved, electrical connections being indicated at 13 and 14.

The stream of resolution products passes through a pipe 15 to the centrifugal apparatus. This pipe should be of as large diameter as may be convenient, should be smooth inside, and should be free from any sharp turns. Steel or copper tubing bent to long radii is to be preferred to pipe and fittings for this purpose.

10 Numerous types of centrifuge are available for subjecting the resolved stream to centrifugal force, but I prefer the apparatus generally indicated at 16 as subjecting the mixture of resolution products to the least possible disturbance prior to separation of the phases.

The specific centrifugal machine indicated at 16 consists of a bowl 17 tapering upwardly and, preferably, having a slightly depressed bottom 18. The bowl is suspended in a frame having uprights 20—20 connected by an upper spider 22 and a lower spider 23. Centrally of the upper spider is a bearing 21 in which revolves a stub shaft 24 projected upwardly from the upper end of the bowl. At the center of the lower spider 25 is situated a bearing 25 in which rotates a hollow

shaft 26 projecting downwardly from the bottom of the bowl. For simplicity plain bearings are shown, but in practice frictionless bearings would be used. The hollow shaft 26 is provided with a pulley 27 or other means for revolving the bowl at the requisite speed.

The end of tube 15 is directed upwardly within hollow shaft 26 as at 28 and is terminated at the lowermost point of the bottom of the bowl. The portion 28 of the tube should be machined to a free sliding fit within the hollow shaft and a packing box 29 may be provided at the lower end of the shaft to prevent leakage.

Within the bowl a stiff rod or tube 30 is projected downwardly from the upper end of the bowl and supports a sheet metal cone 31 in a position substantially parallel to the bottom of the bowl. This cone, which revolves with the bowl, is spaced from its bottom by a distance which may more or less equal the diameter of the inlet pipe 28.

At the extreme outer and lower edge of the bowl we place a water outlet 32 which must be provided with some means for controlling the quantity of liquid flowing therethrough, as for example the valve 33. This outlet connection, which of course revolves with the bowl, discharges into a ring shaped channel 34 suspended from the frame in a fixed position surrounding the bowl. This channel, shown in cross-section and on an enlarged scale in Fig. 3, has a slot 35 in which nipple 32 travels, and an incurved edge 36 to prevent liquid forcibly projected into the channel from being thrown back out of the slot, and is provided with one or more drainage outlets 37.

At or near the upper end of the bowl we provide a similar outlet nipple 38 which discharges into a collecting ring 39 provided with a drainage outlet 40. This nipple needs no valve control and is preferably extended inwardly to the center of rotation of the bowl. It will be understood that a single outlet or a plurality of outlets arranged unsymmetrically should be counter-balanced by suitable weights fastened to the bowl in such position as to bring it into running balance.

This assembly functions in the following manner. The stream of resolution products—water, oil, and emulsifying agent—produced in treater 10 flows through tube 15—28 into the space between bowl bottom 18 and cone 31. In this space the lineal velocity of the stream is retarded and it is set in revolution at a gradually increasing velocity as the liquid flows outwardly. The liquid mass in the bowl being in rapid revolution, the water and any solid substances acting as emulsifying agents are forced to the periphery of the bowl from which they are continuously withdrawn by outlet 32 at a controlled rate. Oil freed from water by centrifugal force collects in the central and upper portion of the bowl from which it is discharged through nipple 38. This outlet will remove any proportion of the feed which is not withdrawn by valved outlet 32 and consequently needs no control. Solids heavier than water are in part projected against the outer wall of the bowl, and gradually pass downward to the outlet due to the flare of this surface.

In handling crude petroleums of high viscosity it is often necessary to heat them to the atmospheric pressure boiling point of water, or to some lower superatmospheric temperature at which dissolved gases are evolved, in order to render them amenable to electrical resolution and to centrifugal separation. If oils so heated are passed into the centrifuge at atmospheric pressure, the evo-

lution of steam or gas in the bowl interferes very seriously with the separation by centrifugal force.

In such cases I prefer to use the modified form of apparatus illustrated in Fig. 4. In this form 5 of the invention the bowl 17 is suspended between upper and lower frame members 22 and 23 (of which only fragments are shown) in bearing elements indicated at 21 and 25. To the bottom of the bowl is affixed a flanged collar 26 10 carrying a driving pulley 27. Inside this collar is fixed a relatively wide tube 41 which revolves with the bowl.

Inside the bowl a circular plate 42, arranged parallel with its bottom, is supported by a plurality of standards 43 and at the center of revolution of this plate is fixed a feed pipe 44 concentrically arranged within pipe 41. This pipe discharges above plate 42 and below a cone 31 which is supported from plate 42 by a plurality 20 of standards 45.

The feed pipe 15, which is in fixed position, is coupled to feed pipe 44 by any desired form of packed swivel joint 46. A water outlet pipe 47 having a control valve 48, which is held in 25 fixed position, is affixed to a double packed swivel joint 49 inside which pipes 41 and 44 revolve. An oil outlet pipe 51, which is illustrated as forming the upper support for the bowl, is projected upwardly from the top of the bowl 30 and is coupled to an oil discharge pipe 52, held in fixed position and provided with a control valve 53, by means of a packed swivel joint 54 inside which pipe 51 revolves.

In the use of this form, which may be maintained under any desired pressure by regulation of valves 48 and 53, the mixture of oil and water enters the bowl above plate 42 and below cone 31. Separated water returns from the periphery 40 of the bowl beneath plate 42 to pipe 41 by which it is discharged into water outlet pipe 47. Separated oil is withdrawn from the upper end of the conical bowl through pipe 51 by which it is discharged into oil pipe 52.

45 We claim as our invention:

1. Apparatus for separating the constituents of a loose mixture of oil and water, comprising: a substantially closed vessel having a flat bottom; means for maintaining said vessel in rotation on its vertical axis; an axial inlet tube for said mixture of oil and water extending a short distance into said vessel from the bottom; an axial oil outlet tube fixed to the upper end of said vessel; an axial water outlet tube placed around 50 said inlet tube and ending at the bottom of said vessel; a partition attached to the upper end of said inlet tube, setting off between itself and the bottom of said vessel a space communicating only with the peripheral region of the remainder of said vessel and with said water outlet tube; a spreader plate setting off between itself and said partition a substantially unobstructed, approximately disc-shaped space having a thickness similar to the diameter of said inlet tube, said plate having its periphery in the radially intermediate region of said vessel; a stationary water pipe and a swivel joint connecting it with said water outlet tube; a stationary oil pipe and a swivel joint connecting it with said oil outlet tube; and adjustable valves in said stationary oil and water pipes for maintaining a desired back pressure in said vessel.

2. In an apparatus for the separation of constituents of a petroleum emulsion including means for electrically treating a flowing stream

of said emulsion, a centrifugal separator for separating the oil and water phases and means to conduct treated emulsion from said electrical treating means to said centrifugal separator; a conduit for conducting said treated emulsion from said treating means to said separator comprising a smooth walled channel connected with the discharge of said electrical treating means and with the intake of said separator and a centrifuge vessel comprising an intake port in 10 the lower surface thereof and substantially con-

centric with the axis thereof, a deflector plate substantially concentric with the axis of said vessel, extending to a point intermediate the axis and the peripheral wall of the centrifugal vessel, and spaced from said intake port a distance in the nature of the diameter of said port, means to rotate said vessel and means for separately withdrawing oil and water from said vessel.
